CANDLE HOLDER

Rolf Törnström, Nattrabyhamn, Sweden

Application February 13, 1950, Serial No. 7,918
In Sweden August 24, 1949

Term of patent 3½ years

(Cl. D48—2)

To all whom it may concern:

Be it known that I, Rolf Törnström, a subject of the King of Sweden, and a resident of Nattrabyhamn, Sweden, have invented a new, original and ornamental Design for a Candle Holder, of which the following is a specification, reference being had to the accompanying drawing, forming a part thereof.

The single drawing figure is a perspective view of a candle holder, showing my new design.

I claim:

The ornamental design for a candle holder, substantially as shown.

ROLF TÖRNSTRÖM.
